UNITED STATES PATENT OFFICE.

CHARLES D. GOLDEN, OF CHICAGO, ILLINOIS.

DESIGN FOR A CLOCK-CASE.

SPECIFICATION forming part of Design No. 26,824, dated March 30, 1897.

Application filed February 9, 1897. Serial No. 622,670. Term of patent 3½ years.

To all whom it may concern:

Be it known that I, CHARLES D. GOLDEN, a citizen of the United States, residing at Chicago, in the county of Cook and State of Illinois, have invented and produced a new and original Design for Clock-Cases, of which the following is a specification, reference being had to the accompanying drawing, embodied in one figure, showing a front elevation of a clock-case illustrating my design.

The leading feature of my design consists of a portière or curtain suspended over and arranged to hide what would appear to be an archway supported by columns, the portière forming a background for two female figures, one upon the right and the other upon the left hand, while the clock-face occupies the upper central space.

Referring to the drawing, a represents a portière draped from an archway supported by columns of which the upper portions b b only are shown. Brackets c serve as supports for the main portion of the columns d, which are spirally molded, as shown, and surmounted by capitals e. Horizontal portions ff, of ornate molding, serve to flank a central semicircular arch g. Urns h h in turn surmount the parts ff. A central scalloped ornament crowns the arch and is flanked by foliation in conventional form. A clock-face i is centrally located below the arch, above which is represented an eagle with outstretched wings, a shield upon its breast, a scroll in its beak, and an olive branch and arrows in its talons. A flag upon each side of the clock flanks the figure of the eagle.

In the left-hand foreground is represented the figure of a woman adorned in fanciful costume, ornamented by leaves and fruits, bearing a salver upon which are wines, fruits, and flowers. In the right-hand foreground is shown a second female figure, similarly costumed, bearing a falcon upon her right hand, while the left hand rests upon the head of a large dog. From the girdle of each woman is suspended a bunch of keys. The central space between the figures and below the clock-face is occupied by an oblong panel surrounded by a beaded frame. The figures and ornamentation are intended to be represented in low relief, while a suitable molding at the bottom representing steps serves as a base for and helps to balance the structural effect.

The design for a clock-case, substantially as described and shown.

In testimony whereof I have signed this specification, in the presence of two subscribing witnesses, this 3d day of February, 1897.
